ANTISOILING GARMENT CATCHER FOR IRONING BOARDS

Filed Dec. 4, 1950

UNITED STATES PATENT OFFICE

2,635,369

ANTISOILING GARMENT CATCHER FOR
IRONING BOARDS

Thelma V. Baker, Fort Wayne, Ind.

Application December 4, 1950, Serial No. 199,007

4 Claims. (Cl. 38—111)

1

The present invention relates to certain new and useful improvements in anti-soiling shields and garment catchers commonly used, in many and varied ways, in association with and usually underneath an ironing board.

The art to which the invention relates is highly developed and quite active and reveals numerous styles and types of anti-soiling garment protectors. These are referred to as ironing board attachments, shields, baskets, slings, aprons and so on. Broadly, and generally construed, these types of devices employ a fabric, canvas or similar catcher and various ways and means whereby same is attached to and suspended by some part of a folding ironing board construction. The trend of demands in this line of endeavor may be said to call for and indorse a form of protector which will fully underlie the ironing board and which will preferably rest on the floor in a manner to prevent draping sheets and articles of bedclothing, tablecloths and other large articles from hanging down in soiling contact with the floor or other surface during the act of ironing. In fact, certain cot-like protectors have been evolved and used by others.

It is an object of the instant invention to structurally, functionally and otherwise improve upon known prior art anti-soiling protectors and, in so doing, to provide an acceptable and satisfactory construction in which manufacturers, users and others will find their essential needs fully met, contained and effectually available.

Another object of the invention is to provide an anti-soiling garment catcher and protector in the field stated wherein a simple apron is employed, said apron being provided at corner portions with flexible tying elements and the latter being tied to suitable keepers provided therefor on a framework which underlies and supports the apron.

Another object of the invention is to provide a framework and apron assembly wherein both the apron and framework are constructed to permit a portion of a supporting leg of the ironing board frame to have unobstructed bearing contact with the floor.

More specifically, novelty is predicated on an apertured piece of canvas or the like providing a suitable apron, the same being rectangular, provided at corner portions with flexible ties and said ties being connected with suitable keepers on the end portions of a substantially X-shaped framework, the latter being collapsible and foldable into compact form for convenient storage, when not in use.

2

Other objects and advantages will become more readily apparent from the following description and the accompanying sheet of illustrative drawings.

5 In the accompanying drawings wherein like numerals are employed to designate like parts throughout the views:

Figure 1 is a perspective view of a conventional type folding ironing board construction 10 and the folding cot-like anti-soiling garment catcher constructed in accordance with the invention and showing the manner in which it is used in conjunction with the ironing board construction;

15 Figure 2 is a perspective view of the framework per se in its open or expanded ready-to-use form;

Figure 3 is an enlarged elevational view showing 20 the manner in which the sections or frames of the over-all framework are folded for compact and convenient storage; and,

Figure 4 is an enlarged fragmentary horizontal section on the plane of the line 4—4 of Figure 2, looking in the direction of the arrows.

25 Referring now to the complete assemblage illustrated in Figure 1, the numeral 6 denotes the ironing board construction on the one hand, while the numeral 8 denotes the cot-type garment catcher on the other hand. The construction 6, of course, constitutes no part of the invention but perhaps may be best described, somewhat briefly, as embodying legs 10—10 supporting one end of the ironing board 12, converging braces 14—14 joined with the legs and the ironing board, and a V-type front leg unit 16 provided with stays 18—18.

The anti-soiling garment catcher is characterized chiefly by two main components; namely, a so-called collapsible X-shaped framework and 40 an apron detachably tied thereon. The framework is actually made up of four complementary generally rectangular frames. There are two short frames 20 and 22 and two relatively long frames 24 and 26. Each frame is of general 45 rectangular form although it will be noticed that the inner vertical end portions are appreciably narrower than the outer vertical end portions. It follows that the narrower ends of the respective frames converge toward the hub area 50 at which point a special linking clamp 28 is provided. The clamp comprises a pair of flat plates 30 and 32 which are shown in Figure 4 are bolted together at 34 and retained by a fastening nut 36. The plates have semi-circular 55 bends 38—38 at corresponding ends and similar

bends 40—40 at opposite corresponding ends. These bends are opposed and provide suitable bearings for the vertically disposed journal portions 42—42 and 44—44 of the respective frames 20 to 26 inclusive. Thus, the over-all framework is of general X-shape form as best shown in Figure 2 and the X is actually made up of two pairs of relatively long and short companion frames. The latter are of general rectangular outline and the inner narrower ends are clamped and hinged together to render said frames collapsible or foldable, as brought out in the compact drawing of same in Figure 3. In order to fold the frames, the two frames 24 and 26 are swung toward each other as denoted as by the arrows A—A. The shorter frames are swung away from each other in the direction of the arrows B and C and are folded against the collapsed frames 24 and 26 as is obvious. Figure 2 therefore shows the X-frame expanded and ready for use and Figure 3 the frames in folded positions wherein the over-all device is ready to store away. It will be noticed that by tapering the frames or gradually narrowing same in width from their outer toward their inner clamped ends, the outer corner portions of the respective frames, all denoted by the numerals 46, function as feet and the latter bear in a limited contact manner on the floor or other support. The upper corner portions 38 of all of the frames are provided with diagonal suitably fastened strip members 50 defining a series of four so-called keepers. The lower limbs 52 of all of the frames slant upwardly and inwardly toward the hub portion or clamp and these limbs thus clear the floor to prevent direct wiping or rubbing contact with the floor and they also define the aforementioned feet 46. The upper limbs, while less important, are denoted by the numerals 54 and these limbs, by tapering inwardly and downwardly permit the canvas or equivalent apron 56 to "sink" slightly at the center. The apron is of general rectangular form and has a marginal binding 58. The corner portions are provided with suitable ties 60 and all of these ties are separably connected with the corner keepers on the framework. There is an opening at 62 with a marginal binding 64 which opening accommodates the adjacent end portion of the leg frame 16.

In use, the apron is taut and spans and overlies the framework and is connected thereto by the ties 60 in the manner shown. The ties may be unfastened in an obvious manner, the apron rolled up and the frame collapsed and folded up and the parts put away in limited storage quarters in an obvious manner.

A careful consideration of the foregoing description in conjunction with the invention as illustrated in the drawings will enable the reader to obtain a clear understanding and impression of the alleged features of merit and novelty sufficient to clarify the construction of the invention as hereinafter claimed.

Minor changes in shape, size, materials and rearrangement of parts may be resorted to in actual practice so long as no departure is made from the invention as claimed.

Having described the invention, what is claimed as new is:

1. An anti-soiling garment catcher of the class described comprising an apron and a framework

for supporting the apron, said framework being made up of complementary pairs of relatively long and short individual frames, the inner adjacent end portions of the respective pairs of frames being in close proximity, and hinging and clamping means securing said inner end portions together.

2. An anti-soiling garment catcher of the class described comprising an apron, having an opening adapted to receive the front leg of an ironing board, and an X-shaped framework for supporting said apron, said framework being made up of pairs of converging relatively long and short individual frames, the inner converging end portions of the respective pairs of frames being in close proximity, and hinging and clamping means securing said inner end portions together, said frames being wide at their outer ends and narrow at their ends and said outer ends having keepers, said apron being provided with tie elements adapted to be connected with said keepers when the apron is used in combination with said frame work.

3. A folding frame adapted to support an anti-soiling garment catcher apron comprising a hinging and coupling clamp, a pair of relatively short frames disposed in opposable relationship and having their respective inner ends hingedly connected with one end of said clamp, a complementary pair of longer frames disposed in a relationship opposed to each other and connected at their inner ends to the opposite end of said clamp, the respective pairs of frames being disposed in converging relationship in respect to each other and the converging ends being directed toward said clamp.

4. A folding frame adapted to support an anti-soiling garment catcher apron comprising a hinging and coupling clamp, a pair of relatively short frames disposed in opposable relationship and having their respective inner ends hingedly connected with one end of said clamp, a complementary pair of longer frames disposed in a relationship opposed to each other and connected at their inner ends to the opposite end of said clamp, the respective pairs of frames being disposed in converging relationship in respect to each other and the converging ends being directed toward said clamp, said frames being relatively wide at their outer ends and narrower at their inner ends, and an anti-soiling apron adapted to be spread over said framework when the latter is in position for use, said apron having ties at its respective corner portions adapted to be detachably tied to the outer ends of the respective frames and said apron being provided at one end with an opening which is adapted for passage of a supporting leg on an ironing board, said opening being adapted to be disposed centrally between the frames of the coacting pair of frames.
